INVENTOR,
Robert A. Johnson,
BY *W. J. Bellomy*,
ATTORNEY.

UNITED STATES PATENT OFFICE.

ROBERT A. JOHNSON, OF SPRINGFIELD, MASSACHUSETTS.

ATTACHMENT FOR CALIPERS.

1,234,342.

Specification of Letters Patent. Patented July 24, 1917.

Application filed August 16, 1915. Serial No. 45,622.

To all whom it may concern:

Be it known that I, ROBERT A. JOHNSON, a citizen of the United States of America, and resident of Springfield, in the county 5 of Hampden and State of Massachusetts, have invented certain new and useful Improvements in Attachments for Calipers, of which the following is a full, clear, and exact description.

10 This invention relates to an improvement in a calipers, more especially a micrometer calipers of the form comprising an approximately semi-circular yoke, the outer jaw of which is formed with a convex anvil member, while through the other portion of 15 the yoke and the barrel extension thereof the movable and measuring or gaging jaw of the device is comprised,—the invention more particularly relating to a simple form 20 of removable appliance or attachment to be made use of for the measuring of an article or piece, one surface of which is concave and which could not be measured or gaged with exactness between flat ends of the anvil 25 jaw and the measuring jaw.

The improved device is fully described in conjunction with the accompanying drawings and is set forth in the claim.

In the drawings:

30 Figure 1 shows a side view of a micrometer calipers of well known and extensively used kind having the improved detachable appliance in place on the anvil provided jaw thereof.

35 Fig. 2 is a sectional view through the anvil comprising jaw with the device in its place thereon.

Fig. 3 is a perspective view of the device.

40 Figs. 4 and 5 are views to indicate by comparison between Figs. 5 and 4 the practical advantage derived in the use of the device.

In the drawings, A represents the yoke of the calipers having the barrel extension B,— 45 a representing the anvil member or jaw, and b representing the movable shaft or measuring or gaging jaw.

The outer extremity d of the yoke,—of which the anvil member a is formed as a 50 cylindrical inward extension or boss,—has a rounded or hemi-cylindrical edge,—such being the usual contour or design of this part as usually made.

The detachable appliance D consists of a 55 partially cylindrical clip or sleeve f to con-

strictively embrace the outer face or rounded edge and the opposite sides of the jaw d, the same having at its inner end, that is its end, which when the clip is assembled on the calipers lies toward the jaw d, a wall 60 g to overlie the end of the anvil member a, such wall being extended to convergence substantially to a point in the axis of the device.

As represented, the convergent portion g² 65 of such wall is of the form of a hemisphere.

The said wall has a short, curved flange h, opposite from and continued with the rounded back of the partially cylindrical clip or sleeve for engagement with the end of the 70 anvil member a, as particularly represented in Fig. 2.

The split sleeve-like portion or clip f of the appliance is provided with outwardly turned lip portions j j at its opposite sides 75 substantially as represented, for facilitating the engagement of the device on the portion d of the caliper frame.

When the appliance is to be used, it is positioned on the jaw d with the inner face 80 of the wall g against the anvil member and with the back of the clip closely against and with constrictive engagement around the jaw,—the curved flange h preventing displacement of the appliance from its position truly axial with the members a and b, and the constrictive back portion of the clip overcoming any tendency of the appliance to creep away from the end of the anvil to impair the accuracy of the instrument. 90

With reference to Fig. 4, it will be seen that in attempting to measure a piece,—as for instance a ring or the wall of a cylinder,—the concaved side of such piece would 95 only have bearing against the anvil member at the opposite corners thereof,—the end face of such member forming the chord of an arc and so that the distance between the gaging parts of the instrument is not a true 100 measurement of the thickness; but as will be perceived in Fig. 5, the point in the hemispherical portion g² of the attachable and detachable appliance, coincident with the common axis of the anvil and the jaw b, 105 may be brought against the concave surface to gage with precision the true thickness of the piece.

The device may be integrally made as to the greater portion thereof of thin spring 110

metal at insignificant cost; and it constitutes an extremely useful auxiliary to a calipers.

I claim:—

5 An appliance for a calipers consisting of a split or partially cylindrical constrictive sleeve, to embrace the edge and opposite sides of the anvil provided jaw-member of a calipers, such sleeve being provided with 10 outwardly turned lip portions at its opposite sides, and which also has a wall at one end thereof to be in contact against the end of the anvil of the calipers and which wall

has an extension, to project toward the movable gaging member of the calipers, which 15 is convergent to the common axis of the anvil and movable gaging member, and which clip also has an annular flange adjacent said end wall to engage around the portion of the anvil adjacent the end. 20

Signed by me at Springfield, Mass., in presence of the subscribing witness.

ROBERT A. JOHNSON.

Witness:

G. R. DRISCOLL.
